(57) CLAIM

The ornamental design for can or bottle holder for boats, as shown and described.

DESCRIPTION

A plastic or stainless steel hollow cylinder shaped can or bottle holder, which is open at the top and has a closed bottom with holes for easy draining. The upper edge of the hollow cylinder has an upright arm with a hooked upper end. This hook may be fastened over a safety rail, such that the beverage holder automatically pivots with the rocking motion of a boat in water. Consequently, spillage can be avoided and the drink can be stabilized, if the can or bottle is placed in the can or bottle holder.

FIG. 1 is a side view of my design;

FIG. 2 is a frontal perspective view;

FIG. 3 is a back perspective view;

FIG. 4 is a top perspective view showing the drain holes in the bottom and the mounting clip; and,

FIG. 5 is a bottom perspective view.
